STANLEY G. JOHNSON, OF GROSSE POINTE VILLAGE, MICHIGAN

LOOSE LEAF BINDER

Application filed January 7, 1932. Serial No. 585,329.

This invention relates to covers for books or loose leaf binders and more particularly to structures of this type wherein the lids of the cover and a support cooperate in easel fashion in supporting the book or loose leaf binder in an open standing position so that the leaves or pages may be conveniently viewed.

An object of the invention is to provide a self-supporting cover of this type which embodies a back member to which the lids are hingedly connected and a supporting leg pivoted to the back member; both the back member and supporting leg being so shaped cross-sectionally as to permit the leg and back member to nest or interfit one within the other and thereby reduce the combined cross-sectional area of the back member and supporting leg to a minimum when the cover is in closed position. This arrangement not only reduces the storage space of a book or loose leaf binder constructed in accordance with my invention but renders the cover neat and attractive by reason of the leg and back member being maintained in nested or interfitting relation when the book or loose leaf binder is being handled or stored on a shelf.

The invention further provides a combined book or loose leaf binder cover wherein a pivoted leg or support is carried by the back of the cover for cooperation with the lids thereof in supporting the book or loose leaf binder in standing open position and which is arranged to embrace the book back when the leg is not in use and thereby serve as a reinforcement for the back as well as to maintain the leg in true parallel relation to the back when the leg is in this last mentioned position.

Another object of my invention is to generally simplify prior structures of this character by constructing the supporting leg to cooperate with the back member in holding the supporting leg and back member in fixed relation when the cover is arranged in standing open position.

The invention also provides latch means cooperating with the supporting leg and cover in maintaining the supporting leg against accidental pivotal movement when the latter occupies the back embracing position; the latch means being such as to permit its ready disengagement when it is desired to move the leg to operative position.

With the foregoing and other objects and advantages in mind the invention consists in the novel combination of elements, constructions, arrangements of parts and operations to be hereinafter specifically set forth, claimed, and illustrated in the accompanying drawings wherein:

Figure 1 is a front elevation of a loose leaf binder embodying my invention and in open position;

Figure 2 is an upper edge elevation of the same and showing the supporting leg in operative position;

Figure 3 is a similar view but illustrating a different retention means for the loose leaves;

Figure 4 is a view similar to Figure 1 having the loose leaf retention means shown in Figure 3;

Figure 5 is an enlarged detail view partly in vertical section at the back of the cover and partly in elevation, the supporting leg being in back embracing or inoperative position;

Figure 6 is a view partly in transverse section and partly in elevation with the lids in closed position and the leg in back embracing position;

Figure 7 is a view similar to Figure 6 but illustrating the loose leaf retention means illustrated in Figure 4;

Figure 8 is a fragmentary perspective particularly illustrating the relation of the supporting leg, back member and lids when the device is in standing position;

Figure 9 is a perspective of the loose leaf

retention member illustrated in Figures 3, 4 and 7; and

Figure 10 is a perspective of the invention in standing open position.

Referring to the invention in detail a channel-shaped back member 5 formed from stiff material such as sheet metal is provided and with the two lids 6 constitutes a cover for a book or loose leaf binder. As shown in Figure 6 the flanges or parallel portions of the channel-shaped back member extend inwardly toward the rear longitudinal edges of the lids 6 and are hingedly connected with the lids by flexible or fabric sheets extending over the opposite faces of the back member and lids and suitably secured thereto.

Cooperating with the lids 6 in supporting the cover in open standing position in easel like fashion is a pivotally mounted channel-shaped supporting leg 8. This supporting leg is arranged with its flanges or parallel portions extending toward the back member 5 and is slightly larger in cross-section than the back member so that the supporting leg and back member may be nested or interfitted one within the other to completely house the back member when the supporting leg is not in use.

The upper ends of the flanges or parallel portions of the supporting leg lie upon the outer faces of the flanges or parallel portions of the back member and are pivoted thereto by pivot pins 9 passing through these parts and extending into the ends of a sleeve 10 arranged between the flanges of the back member at its upper end.

In order to maintain the supporting leg and back member in fixed divergent relation when the supporting leg is swung outwardly to standing position to cooperate with the outstretched lids in supporting the cover in standing open position the upper end of the supporting leg has its web cut away to produce a horizontally extending shoulder or abutment 11 slightly below the upper end of the back member. With the supporting leg in standing position the shoulder or abutment 11 engages the outer face of the back member as illustrated in Figures 8 and 10 and thereby maintains the supporting leg and back member in fixed divergent relation so that the cover will stand in easel-like fashion without collapsing. It will be observed that my improved cover does not necessitate a brace or connection between the supporting leg and back member. The supporting leg is given the desired finish by covering all of its surfaces with suitable flexible material or fabric 12.

For the purpose of maintaining the supporting leg against accidental movement when it occupies the back embracing position a suitable latch device is provided between the cover and supporting legs. In this instance the latch device consists of a female

fastening or resilient socket 13 carried by the web of the supporting leg adjacent its lower or free end and a cooperating male fastening element 14 which projects laterally from the web of the back member 5 at a point opposite the female fastening or socket so as to enter the latter to detachably couple the parts 13 and 14 together. It will be observed that a slight pull upon the free end of the supporting leg will disengage the parts 13 and 14 and permit the supporting leg to be swung outwardly to operative position.

It will be observed that when the supporting leg embraces the back member as above stated it will be in a position where it will not interfere with the opening of the cover and pages or leaves carried therein while the cover occupies a horizontal position on a table or other support. Moreover, the channel-shaped supporting leg acts as a protective or reinforcing housing for the back member, thus adapting the cover to rough usage or handling without mutilation. It will also be apparent that the supporting leg cannot move on its axis when the cover is being handled due to the fact that the back member and supporting leg are latched together by the cooperating male and female fastening 14 and 13.

The invention proposes the use of any well-known form of loose leaf binder for use in the cover and for illustrative purposes I have herein disclosed two forms of loose leaf binder. One of these consists of a sheet metal transversely bowed housing 15 which is opposed to the inner face of the web of the back member 5 and extends substantially the entire length thereof. Suitable attaching elements such as rivets 16 pass through the end portions of the housing 15 and the web of the back member to anchor the housing thereto. Hingedly connected plates 17 are confined between the inner face of the back member and the housing 15 and carry coacting half rings or curved prongs 18. These half rings or curved prongs project forwardly from the plates 17 and extend through openings 19 in the longitudinal edges of the housing.

The second embodiment of the binder comprises a channel-shaped member 20 having its web or intermediate portion anchored to the inner face of the back member as at 21 and has pairs of coinciding eyelets 22 provided in its parallel flanges. Suitable fastenings such as two-part binding posts 23 extend through each pair of eyelets and the usual perforations in the loose leaves (not shown).

What is claimed is:

1. In combination a book cover having lids, and a supporting leg pivoted to the book cover back and arranged to cooperate with the lids in supporting the cover in easel-like fashion, the supporting leg being shaped to conform to the contour of the book back 139

- so as to embrace the same when the leg is not in use.
2. In combination a book cover having lids and a rigid back member hingedly connected with the lids, and a supporting leg pivoted to the back member and arranged to cooperate with the lids in supporting the cover in easel-like fashion, the supporting leg being shaped to conform to the contour of the back member and adapted to embrace the same when the leg is not in use. 70
- 10 3. In combination a book cover having lids, and a supporting leg pivoted to the book cover back and arranged to cooperate with the lids in supporting the cover in easel-like fashion, the supporting leg being shaped to conform to the contour of the book back so as to embrace the same when the leg is not in use, and means for latching the leg to the cover when the leg is in the book back embracing position. 75
- 15 4. In combination a book cover having lids and a rigid back member hingedly connected with the lids, and a supporting leg pivoted to the back member and arranged to cooperate with the lids in supporting the cover in easel-like fashion, the supporting leg being shaped to conform to the contour of the back member and adapted to embrace the same when the leg is not in use, cooperating latch elements carried by the leg and back member to latch the leg thereto when the latter is not in use. 80
- 20 5. In a book structure, a back member, lids hinged to opposite sides thereof, a supporting leg pivoted to the upper end of the back member and adapted to cooperate with the lids in supporting the book structure in easel-like fashion, the leg being so shaped cross-sectionally as to receive and house the back member when the leg is moved to lie parallel to the back member. 85
- 25 6. In a book structure, a back member, lids hinged to opposite sides thereof, a supporting leg pivoted to the upper end of the back member and adapted to cooperate with the lids in supporting the book structure in easel-like fashion, the leg being so shaped cross-sectionally as to receive and house the back member when the leg is moved to lie parallel to the back member, and latch means for holding the leg in the last mentioned position. 90
- 30 7. In a book structure, a back member, lids hinged to opposite sides thereof, a supporting leg pivoted to the upper end of the back member and adapted to cooperate with the lids in supporting the book structure in easel-like fashion, the leg being so shaped cross-sectionally as to receive and house the back member when the leg is moved to lie parallel to the back member, and cooperating fastening elements between the back member and leg for maintaining the latter parallel to the back member. 95
- 35 8. In combination a book cover including a back member, lids hinged to opposite sides thereof and a channel-shaped supporting leg having its upper end pivotally connected with the back member and arranged to cooperate with the lids and back member in supporting the book cover in standing open position, the upper end of the leg being cut away to provide an abutment for engagement with the back member in maintaining the leg and back member in fixed divergent relation. 100
- 40 9. In combination a book cover including a back member, lids hinged to opposite sides thereof and a channel-shaped supporting leg having its upper end pivotally connected with the back member and arranged to cooperate with the lids and back member in supporting the book cover in standing open position, the upper end of the leg being cut away to provide an abutment for engagement with the back member in maintaining the leg and back member in fixed divergent relation, and a loose leaf binder unit carried by the inner face of the back member. 105
- 45 10. In combination a book cover including a back member, lids hinged to opposite sides thereof and a channel-shaped supporting leg having its upper end pivotally connected with the back member and arranged to cooperate with the lids and back member in supporting the book cover in standing open position, the upper end of the leg being cut away to provide an abutment for engagement with the back member in maintaining the leg and back member in fixed divergent relation, and cooperating male and female fastening elements carried by the leg and back member and arranged to secure the leg in a position to house the back member when the cover is closed. 110
- 50 11. In combination a book cover having rigid lids and a rigid back member hingedly connected with the lids, and a supporting leg pivoted to the back member and arranged to cooperate with the lids in supporting the cover in easel-like fashion, the supporting leg being shaped to conform to the contour of the back member and adapted to embrace the same when the leg is not in use, and a loose leaf binder unit attached to the inner face of the back member. 115
- 55 12. In a book or loose leaf cover, a rigid channel shaped back, lids hinged to the parallel portions of the channel shaped back, a supporting leg pivoted to the back and arranged to be disposed in divergent relation to the opened lids and cooperate therewith in supporting the cover in easel-like fashion and an abutment carried by the hinged end of the supporting leg and engageable with the back to maintain the supporting leg and back in fixed divergent relation to prevent collapse of the cover. 120
- 60 13. In a book or loose leaf cover a rigid 125
- 65

channel shaped back, lids hinged to the parallel portions of the channel shaped back, and a supporting leg hinged to the back and arranged to be disposed in divergent relation to the back and opened lids and cooperate therewith in supporting the cover in easel-like fashion, the upper end of the leg constituting an abutment for engagement with the back to maintain the supporting leg and back in fixed divergent relation.

10 In testimony whereof I affix my signature.
STANLEY G. JOHNSON.
